(57) **CLAIM**

The ornamental design for a cooktop burner control for glass ceramic cooktop panel, as shown and described.

DESCRIPTION

FIG. 1 is perspective view of a cooktop burner control for a glass ceramic cooktop panel showing our ornamental design;

FIG. 2 is a plan view of the cooktop burner control for a glass ceramic cooktop panel shown in FIG. 1;

FIG. 3 is a bottom view showing that the bottom of the cooktop burner control for a glass ceramic cooktop is unadorned;

FIG. 4 is a front view of a cooktop burner control shown in FIGS. 1-2 and is typical of a front view for each of the embodiments of my ornamental design shown in FIGS. 8-12;

FIG. 5 is a rear view of a cooktop burner control shown in FIGS. 1-4 and is typical of a rear view for each of the embodiments of my ornamental design shown in FIGS. 8-12.

FIG. 6 is a left side view of a cooktop burner control shown in FIG. 1 that is typical of the left side view of each of the embodiments of my ornamental design shown in FIGS. 8-12;

FIG. 7 is a right side view of a cooktop burner control shown in FIGS. 1-3 and is typical of the right side view for each of the embodiments of my ornamental design shown in FIGS. 8-12;

FIG. 8 is an enlarged partial top plan view of a second embodiment;

FIG. 9 is an enlarged partial top plan view of a third embodiment;

FIG. 10 is an enlarged partial top plan view of a fourth embodiment;

FIG. 11 is an enlarged partial top plan view of a fifth embodiment;

FIG. 12 is an enlarged partial top plan view of a sixth embodiment, showing of second operating mode of the design;

FIG. 13 is an enlarged partial top plan view of a seventh embodiment;

FIG. 14 is an enlarged partial top plan view of a eighth embodiment; and,

FIG. 15 is an enlarged partial top plan view of a ninth embodiment.

The broken line showing is for illustrative purposes only, and forms no part of the claimed design.
